UNITED STATES PATENT OFFICE.

ARTHUR S. DWIGHT, OF JOLIET, ILLINOIS, ASSIGNOR TO FRED. BENNITT, TRUSTEE,
OF JOLIET, ILLINOIS.

APPARATUS FOR ROASTING AND SINTERING ORES.

No. 916,392.

Specification of Letters Patent. Patented March 23, 1909.

Application filed June 3, 1907. Serial No. 377,056.

To all whom it may concern:

Be it known that I, ARTHUR S. DWIGHT, a citizen of the United States, residing at Joliet, in the county of Will and State of Illinois, have invented certain new and useful Improvements in Apparatus for Roasting and Sintering Ores, of which the following is a specification, reference being had therein to the accompanying drawing.

This invention relates to improvements in apparatus for treating ores, and particularly to those which require roasting and sintering—such as sulfur-carrying copper ores—and are of such nature that once being ignited an internal combustion of some content of the ore-mass can be maintained, provided an oxidizing atmosphere be supplied.

The invention has for its object to produce an apparatus that may be worked automatically and economically in the treatment of such ores for the purpose of reducing them to a sintered mass of convenient form and nature for subsequent treatment in a blast furnace.

In an application filed by me on the 14th day of December, 1906, Serial No. 347,872 I described three forms of mechanism or apparatus for roasting and sintering ore of the character above referred to. One of these forms of apparatus comprised as the ore supporting and carrying means an endless series of receptacles, buckets, pans or pallets flexibly connected to each other by drive chains; another comprised as the ore supporting and carrying means a drum-like body turning about a horizontal axis; and the third included as the endless ore carrier a horizontally rotating table-like or ring-like structure, which is herein described and made the subject matter of this present application.

In the accompanying drawings, Figure 1 is a view, the half to the right being in elevation and the half to the left being in central vertical section. Fig. 2 is a view of the same apparatus, as seen from above, the half to the right being in plan, and that to the left being in plan with the grate sections removed. Fig. 3 is a plan view, and Fig. 4 is a side elevation of another form of apparatus having a table like or ring-like ore-carrier. Fig. 5 shows in perspective a section of the ore-carrying table illustrated in Figs. 3 and 4.

The apparatus upon which the ore is delivered for the roasting and sintering opera-

tion is in the form of an annular box built up of a number of segments, combined with means for delivering the ore thereto, for igniting the ore, for insuring passage of an oxidizing atmosphere through the ignited mass of ore, and for removing the ore after it has become sintered.

In the drawings A represents an annular shaped foundation upon which is supported a circular track B. Upon this track is supported the annular table upon which the ore roasting and sintering operations take place. This table is formed of a number of box-like segments C, bolted together end to end as indicated at c. As represented, the table consists of eight segments, though a greater or less number may be employed as desired. Each segment comprises a bottom 2, an outer curved wall 3, an inner curved wall 4, and two ends 5, 5. Each section is open ended at the top, or is provided with in-turned flanges 6, 7, having rabbeted edges to receive the grate sections D. The grates D may be of any usual or preferred construction, those which I prefer to employ being of the well known herring-bone construction.

The supporting wheels E that run upon the track or rail B are supported in brackets e, depending from the box-like segmental sections C. The inner wall 4 of each segment C is perforated at 8 and a neck, or a short section of pipe, flanged at its ends and indicated at 9, is secured thereto. A pipe or wind-trunk 10 connects each neck 9 with a neck or short section of pipe 11 extending radially from a cylindrical drum 12 situated at the center of the apparatus. This drum connects by a pipe or conduit 13 with a suction-fan 14 which is driven in any suitable manner, as by a belt passing around the pulley 15.

16 represents a pipe or duct for carrying off the gases that may be drawn through the fan from the suction box 12. The central part of the apparatus, including the suction box and its connections with the several segments C, is suitably supported. I have represented a foundation, a, of masonry or suitable material upon which is mounted a circular track F for a set of balls G. The track is provided with an upwardly extending annular flange f within which sets a bearing piece H secured to the suction box and arranged to rest upon the set of balls G. The lower portion of the suction box is preferably of funnel shape, as indicated at

17, and it is to the tapering outside walls of this portion of the suction box that the bearing piece H is preferably secured. The lower end of the funnel shaped portion of 5 the section box is formed into a spout section 18 in which may be mounted a damper 19, thus providing means for clearing the suction box from ashes or other material that may accumulate therein.

10 I indicates a hopper in which the raw ore to be treated is placed and from which it is fed to the grates D, the latter passing under the hopper as the table is rotated. For effecting the rotation of the table I provide 15 the sections C with curved rack or cog segments J, which coming together end to end as the segments are united, constitute a cog-ring or circular rack. With this rack meshes a drive pinion K supported upon a shaft k 20 mounted in suitable frame-work and arranged to be driven by a train of gearing L receiving its power from any suitable source. Directly in front of the hopper there is mounted a roller M arranged to bear upon 25 the ore mass delivered to the grates to smooth or level its upper surface.

It will be observed by reference to the drawings that the grates are not provided with retaining flanges for confining the ore 30 mass delivered thereto, as these are unnecessary when the grates are flat and are horizontally arranged, as shown. Indeed it is desirable to dispense with any retaining flanges as the removal of the sintered 35 mass of ore after the roasting has been completed is facilitated thereby.

Immediately in front of or in advance of the roller M is a gas-pipe N, perforated or provided with jet orifices. This constitutes 40 an igniter for starting the combustion in the ore-mass, the flame produced by the burning gas issuing from the jets of the pipe N impinging upon the smooth surface of the mass of ore. Within each of the 45 pipes 10 there is mounted a butterfly valve 20 adapted when set in one position to close the pipe and when turned in another position to leave the pipe open so that there is free communication between the suction 50 box or drum 12 and the chamber within that box C to which the pipe connects. The stem or shaft 21 of each valve 20 is provided with a set of tappets or arms 22, adapted to engage with stationary stops or pins 23, 55 24, arranged close to the path followed by the stems or shafts of the valves. One of the stops or pins is located just in advance of the igniter N, and operates to set the valves in position to open the pipes, while 60 the other stop or pin is set in position to close the valves a little before the pipes come opposite to the feed hopper I.

O represents a scraper adapted to remove the sintered ore-masses from the grates D. 65 Its front edge o is preferably serrated so as

to assist in breaking up the ore-masses, and lies close to or bearing upon the grate surfaces. The scraper is stationary and is provided with edge flanges o'. The pieces of sintered ore are forced outward along the 70 scraper which also forms a sort of trough, and are delivered upon an inclined feed-board or apron P whence they may pass to cars or other suitable receptacles.

The operation of the apparatus may now 75 be described. Power is applied to the train of gearing L and to rotate the fan 14. The annular horizontally disposed table is slowly turned, the grate sections passing successively under the feed-hopper and by the 80 igniter N, and, after making a nearly complete revolution, past the scraper O. The fine ore material is fed from the hopper upon the grate and is smoothed by the roller and immediately thereafter ignited by the 85 flame from the gas-pipe N. The particular box C that is located under the scraper, the feed hopper and the igniter, is always cut off from communication with the suction mechanism by the valve 20, which has been 90 turned into closing position by the engagement of one of the arms or tappets 22 with the stop or pin 24. Immediately after the ore is ignited, the box or the section C below the recently ignited mass of ore is put into 95 communication with the suction box 12, by the engagement of a tappet arm 22 with the pin 23, which sets the valve to open position, with the result that air is drawn through the mass of ore and the grate into 100 the suction box, thus maintaining an active combustion in the mass of ore lying upon the grate. This condition of affairs, that is, the communication of the segmental box C with the suction fan, is maintained until 105 just before the parts come opposite the edge of the scraper O, when the valve is closed as already described. The speed of the table is so regulated that the ore will be completely roasted and sintered by the time it 110 reaches the scraper, when it will be in fit condition for removal.

It will be understood that the connection of the vertical leg of the pipe 13 leading to the suction fan with the drum or box 12 is 115 such as to permit of the latter rotating with the table without interfering with its connection with the fan, which is stationarily mounted.

The apparatus which has been described 120 insures the formation of a thoroughly roasted, thin porous cake or biscuit in condition admirably adapted for subsequent treatment in a blast furnace and easily removed from the roasting apparatus. The combustion in 125 the ore-mass by which the sulfur or other combustible content is oxidized is from the top downward, so that the particles of the ore with reference one to the other are not agitated by the passage of the air which is 130

drawn through the mass to maintain rapid and perfect combustion.

These advantages have been set out in applications filed jointly by myself and Richard L. Lloyd and need not be further referred to herein.

In Figs. 3 and 4 a modification of the same mechanism is shown. In this case the air trunk or chest R is stationary and the table moves above it. The ore is fed through a hopper I and distributed in a stream along the top of the table. It is fired or lighted at N and is discharged at O. The table is supported by a central vertical shaft or mast Q from which arms q extend down and outward and are secured to the ore supporting part. The operation of this modified form of apparatus will be readily understood. The air is drawn from the box or trunk R by the fan or exhaust 15, the length of the air box being such as to permit the complete oxidizing and sintering of the ore by the time the latter reaches the place of discharge.

In an application for patent filed June 3, 25 1907, by myself and Richard L. Lloyd, jointly, Serial No. 377,058, for apparatus for roasting and sintering ore, we have shown and described a mechanism wherein the supporting and carrying device for the ore is made in a series of sections, flexibly connected together after the manner of an endless chain conveyer, and arranged to travel in vertical planes. And while there are some features of structure and of operation common to the mechanism therein set forth and that herein presented, there are, under some circumstances, advantages incident to a construction of the present character. For example, in mills where there is 30 not available room or space on vertical lines, sufficient to conveniently erect a mechanism of the class having the carrier so constructed and arranged that it will travel in vertical planes, an apparatus of the kind herein is 35 preferable, as it requires but little space vertically and all of the operative parts can be arranged so that they can be readily inspected from the ground level. Moreover, a mechanism of this sort can be so constructed and have its parts so arranged, 40 that there will be no idle part. The hopper or feeder for the ore, and the horizontally moving support and carrier can be so arranged that the point of discharge or unloading of the sinter can be closely adjacent to the hopper or feeder and igniting device. The ore is upon the traveling carrier throughout substantially its entire circuit; power is not consumed in carrying 45 50 55 60 65 70 75 80 85 90 95 100 105 110 115 120 125 130 heavy parts from a working point (the points immediately ahead of the discharge point) through a long distance to the point where the work is commenced.

In another application filed June 19, 1907, 65 by myself and Richard L. Lloyd, Serial No.

377,809, we have shown and described an apparatus for roasting and sintering ore in which is embodied an endless ore support or carrier having its successive ore-receiving sections or parts rigidly secured and all arranged to simultaneously move through a predetermined path about a common axis, the endless ore support there shown being in the form of a drum turning about a horizontal axis. And in said application are 70 presented the broader claims for an endless carrier, the parts of which are rigidly connected and arranged to move simultaneously in a predetermined path. And in still another application filed by myself 75 solely on December 14, 1906, Serial No. 347,872, there are shown and described a number of features of construction and arrangement of parts which, broadly considered, are similar to some of the features presented in the present application. For example, in the said application, Serial No. 347,872, there is presented an ore support and carrier with an air chamber or trunk adapted to supply air and gas to, or receive 80 air and gas from the several successive sections or parts of the ore carried together with a series of air chambers, each adjacent to a part of the ore carrying mechanism. In the said application, Serial No. 347,872, 85 these chambers for the air or gas are combined with an ore holder that travels around a horizontal axis. In the construction of the present application, the air chambers between the main trunk or duct are somewhat differently arranged and travel with the flat horizontally arranged table. I have in the other application, Serial No. 347,872, 90 presented claims relating to both these constructions, as concerns the air chambers, 95 preferring in the present case to have the claims for those parts relate to a horizontal arrangement.

What I claim is:—

1. In an apparatus for roasting and sintering ore by combustion within the ore mass, an ore support or carrier adapted to be moved continuously in a substantially horizontal, substantially circular path, and having a grate surface on which the ore rests while moving in said circular path, substantially as set forth.
2. An apparatus for roasting and sintering ore by combustion in the ore mass, the combination of an endless ore support or carrier having an annular flat grate surface on which the ore rests arranged in a horizontal plane, means for turning the grate surface about a vertical axis, and means for causing air to pass through the ore mass, substantially as set forth.
3. In an apparatus for roasting and sintering ore by combustion in the ore mass, the combination of an endless ore support or carrier formed of separate sections secured

rigidly together, means for moving the ore support in approximately horizontal planes and means for supplying air to support the combustion in the ore mass, substantially as set forth.

4. In an apparatus for roasting and sintering ore by combustion in the ore mass, the combination of a series of grate sections on which the ore is supported, means for moving the said grate sections in approximately horizontal planes, an air chamber under each section, and means connected with each air chamber for causing air to pass through the ore mass on the grate above, substantially as set forth.

5. In an apparatus for roasting and sintering ore by combustion in the ore mass, the combination of an endless ore support or carrier and means for moving the carrier in horizontal planes, a series of separate air chambers arranged under the ore support, and means for successively connecting the said air chambers with means for causing air to pass through the ore masses above the chambers, substantially as set forth.

6. In an apparatus for roasting and sintering ore by combustion in the ore mass, the combination of an endless ore support, a series of separate air chambers arranged under the ore support, an air drum or box, an air moving device connected therewith, and separate connections between the said air drum or box and the said air chambers, respectively, substantially as set forth.

35 7. In an apparatus for roasting and sintering ore by combustion in the ore mass, the combination of an endless movable ore support, means for moving the said support in horizontal planes and a series of air chambers communicating with the ore support and movable therewith, substantially as set forth.

8. In an apparatus for roasting and sintering ore by combustion in the ore mass, the combination of an ore support, means for moving the support in horizontal planes, a series of air chambers communicating with the support, means for causing movement of air to support combustion in the ore masses connected with the said air chambers, and means for putting the said air chambers into communication with and cutting them off from the said air moving means successively, substantially as set forth.

9. In an apparatus for roasting and sintering ore by combustion in the ore mass, the combination of a flat horizontally disposed grate surface on which the ore is placed, a scraper having its edge arranged close to and extending across the grate surface, the scraper being arranged to remove the sintered ore from the grate, and means for moving one of the said parts relative to the other, substantially as set forth.

10. In an apparatus for roasting and sintering ore by combustion in the ore mass,

the combination of a flat, horizontally disposed annular grate surface on which the ore is placed, means for feeding the ore to the grate, a scraper for removing the sintered ore having its edge arranged close to and extending across the grate surface, and means for turning the annular grate surface about a vertical axis, substantially as set forth.

11. In an apparatus for roasting fine ore, the combination of a movable surface upon which the ore is deposited, a feed hopper for the ore, a roller for smoothing the surface of the ore, means for causing air to pass through the ore, and an igniting device between the roller and the last said means, substantially as set forth.

12. In an ore roasting and sintering apparatus, the combination of a grate surface upon which the ore is supported arranged about a vertical axis around which it turns, a centrally disposed air box or drum, separate air chambers communicating with separate sections of the grate surface, separate connections between the several air chambers and the said central air box or drum, air moving apparatus connected with the central air box, and means for cutting off the air chambers successively from the air box, substantially as set forth.

13. In an ore roasting and sintering apparatus, the combination of a circular track, an annular horizontally disposed ore support mounted upon said track, a series of air chambers communicating with separate sections of the said annular ore support, a centrally disposed air box, separate connections between the several air chambers and the said air box, and a bearing or support for the said central air box, substantially as set forth.

14. In a mechanism for roasting ore, the combination of an ore support arranged to carry the ore in a substantially horizontal, substantially circular path, means for feeding the ore to the said support at one point in the circle of its rotation, means for causing air to pass through the ore while it is traveling through the said path, and means adjacent to the ore supplying device for withdrawing the roasted ore from the support at a point near the terminus of the said circular path, substantially as set forth.

15. In an apparatus for roasting ore, the combination of the ore support arranged to rotate in horizontal planes around a vertical axis, means for supplying to the said support a layer or stratum of ore, means for regulating the depth of said stratum and causing it to be substantially uniform throughout, means for igniting the ore at its surface at points adjacent to the depth-regulating device, and means for causing currents of air to pass through the said ore during the period of time from its delivery

- to said support to its discharge therefrom, said support being adapted to permit the withdrawal of the ore therefrom after the roasting, substantially as set forth.
- 5 16. In an apparatus for roasting ore, the combination of an ore support adapted to be moved in a substantially horizontal, substantially circular path around a vertical axis, a gear ring secured to the said support, a driving gear adapted to engage with the said ring, air collecting or guiding mechanism carried by the ore support, supporting wheels or rollers beneath the ore support, and a guide or track for the said wheels or rollers, substantially as set forth. 70
- 10 17. In an apparatus for roasting ore, the combination of the ore support provided with a perforated bottom adapted to hold or restrain the ore mass and also adapted to permit the passage of air therethrough, said support being arranged to rotate in a substantially circular path, a series of air ducts or trunks adjacent to the ore support and adapted to receive and guide the air passing 75 to or through it, an air trunk at the axis of the ore support, and means for causing said axial air trunk to communicate with the said air ducts or trunks successively, substantially as set forth. 80
- 15 18. In an apparatus for roasting ore, the combination with a series of ore supporting grate sections, air chambers located in proximity to the grate sections, a common air duct through which air is caused to move to 85 maintain combustion in the ore on the grate sections, and air pipes or conduits forming constant connections between the said common air duct and the several air chambers, substantially as set forth. 90
- 20 19. In an apparatus for roasting ore, the combination of ore supporting grate sections arranged in a circular series about a vertical axis, a series of air chambers under the said grate sections, means for turning the grate 95 sections and air chambers together about the said vertical axis, and a means common to the said air chambers arranged to cause air to pass through the grate sections and the ore supported thereon, substantially as set forth. 100
- 25 20. In an ore roasting apparatus, the combination of grate sections for supporting the ore arranged in circular series, the grate sections being substantially horizontal and 105 turning about a vertical axis around which the grate sections are arranged, air chambers located under the grate sections, means for turning the grate sections and the air chambers about the said vertical axis, a common air duct through which air is caused to move to maintain combustion in the ore on the 110 grate sections, and air pipes or conduits forming constant connections between the said common air duct and the several air chambers, substantially as set forth. 115
- 30 21. In an apparatus for roasting ore, the combination of grate sections for supporting the ore arranged in a circular series about a center of rotation, a series of separate air chambers located under the grate sections, means for turning the grate sections and the air chambers together about the said center, the common air duct through which air is caused to move to support combustion in the ore upon the grate sections, air ducts or conduits constituting constant connections between the said common duct and the several air chambers respectively, and valve devices by which the flow of air through each chamber may be regulated and controlled. 120
- 35 22. In an apparatus for roasting ore, the combination of grate sections arranged in an endless series, a series of separate air chambers located in proximity to the grate sections, a centrally located air duct or conduit, and radiating or outward extending air pipes or conduits connecting the several air chambers respectively with the central air duct, substantially as set forth. 125
- 40 23. In an apparatus for roasting ore, the combination of grate sections arranged in an endless series, a series of separate air chambers located in proximity to the grate sections, a centrally located air duct or conduit, radiating or outward extending air pipes or conduits connecting the several air chambers respectively with the central air duct, and valve devices located in the outward extending connecting air conduits, substantially as set forth. 130
- 45 24. In an apparatus for roasting ore, the combination of grate sections arranged in an endless series, a series of separate air chambers located in proximity to the grate sections, a centrally located air duct or conduit, air conduits connecting the said central duct with the several air chambers respectively, and means for successively charging with ore the sections of grate adjacent to the air chambers, and for causing the discharge of the ore after it has been roasted, substantially as set forth. 135
- 50 25. In an apparatus for roasting ore, the combination of ore supporting grate sections, a rotating circular frame in which the said grate sections are supported in series, means for supplying ore successively to the grate sections, means for rotating the circular holder in horizontal planes, means for causing currents of air to pass through the grate sections, and means for causing the discharge of the ore from the grate sections successively after it has been treated, substantially as set forth. 140
- 55 26. In an ore roasting apparatus, the combination of a horizontally arranged rotary support, air chambers in the said support, anti-friction devices upon which the said support rests, a series of grate sections in the support arranged in proximity to the 145

6

air chambers, means for turning the said support about an axis of rotation, means located in proximity to the axis of rotation for causing air to pass through the said chambers and through the grate sections, and means for causing the removal of the ore from the grate sections successively after treatment, substantially as set forth.

27. Apparatus for roasting and sintering 10 ores and the like, consisting of a receiving grate for supporting the charge, means for revolving the grate bodily about an upright axis, and means for causing aeriform fluid to traverse the charge, substantially as de- 15 scribed.

28. Apparatus for the metallurgical treatment of ores and the like, consisting of a receiving grate for supporting the charge, means for revolving the grate bodily about 20 an upright axis, means for feeding the charge to the grate in a uniform layer, means for causing aeriform fluid to traverse the charge and grate as it passes a predetermined point in the grate's revolution, substantially as described.

29. Apparatus for roasting and sintering

ores and the like, consisting of an upright hollow mast, an outlying receiving grate for supporting the charge, and aeriform fluid conduits leading from below the grate to the hollow of the mast, substantially as described.

30. Apparatus for roasting and sintering 35 ores and the like, consisting of an upright mast, an outlying grate carried thereby, and means for causing an aeriform fluid to pass through the grate, substantially as described.

31. An apparatus for roasting and sintering 40 ores and the like, consisting of an upright mast, an outlying grate carried thereby, supplementary carrying wheels for assisting in sustaining the grate in its rotary travel, and means for causing an aeriform fluid to pass through the grate, substantially as described.

45 In testimony whereof I affix my signature, in presence of two witnesses.
